(57) **CLAIM**

What is claimed is the ornamental design for a remote control with laser pointer, as shown and described.

DESCRIPTION

FIG. 1 is a top, rear and right side perspective view of a remote control with laser pointer showing our new design; FIG. 2 is a top, front and left side perspective view thereof; FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken lines depict portions of the remote control with laser pointer that form no part of the claimed design.

1 Claim, 6 Drawing Sheets
